UNITED STATES PATENT OFFICE.

ELLSWORTH GABEL, OF HARRISBURG, PENNSYLVANIA.

RECORD HOLDER.

Application filed May 10, 1924. Serial No. 712,355.

To all whom it may concern:

Be it known that I, ELLSWORTH GABEL, a citizen of the United States, residing at Harrisburg, in the county of Dauphin, State 5 of Pennsylvania, have invented certain new and useful Improvements in Record Holders; and I do hereby declare the following to be a full, clear, and exact description of the invention, such as will enable others skilled 10 in the art to which it appertains to make and use the same.

This invention relates to new and useful improvements in containers, and particularly to containers for phonograph records, 15 of the disk type.

One object of the invention is to provide a device of this character wherein a plurality of envelopes are mounted in book form, and wherein all of said envelopes may be 20 moved into jalousied position to display the entire set of records, thus making the selection of the desired record easy.

Another object is to provide a novel means for connecting the envelopes whereby they 25 may be arranged in proper and even stacked relation, when the book, containing such envelopes, is closed, and whereby such envelopes may be easily and quickly moved 30 into jalousied position when the book is open, to facilitate the selection of the desired record.

Other objects and advantages will be apparent from the following description when taken in connection with the accompanying drawing.

In the drawing:

Figure 1 is a perspective view of a record-containing book, made in accordance with the present invention, and shown in open 40 position, with the envelopes in jalousied position.

Figure 2 is an edge view of the book in closed position.

Figure 3 is an enlarged sectional detail 45 view through the connected portions of the envelopes.

Referring particularly to the accompanying drawing, 10 and 11 represent the two boards of the back of the book, which are 50 connected by the hinge portion 12. The free end of the board 10 is formed with a flap 13 which overlaps the free end of the board 11, when the book is in closed position, and carries the socket portion 14, of a fastener which engages with the head portion 55 15, carried by the board 11.

Disposed between the boards 10 and 11 are the envelopes 16, formed preferably of heavy paper, of the character now generally used in this type of record book, said envelopes having their closed ends disposed adjacent the hinge portion 12. One of the envelopes, indicated by the numeral 16', is preferably secured to the board 10.

A strip of cloth 17, of a width equal to 60 that of the envelopes 16, has one end secured between the envelope 16' and the board 10, with its other end free, while the intermediate portion is folded in bellows formation, with the folds extending into the 65 spaces between adjacent envelopes, at the closed ends thereof. One portion of each of these folds, which folds are indicated by the numeral 18, is secured to the inner face 70 of the closed end of the envelope. Extending transversely of each of the envelopes, at the closed end thereof, is a strip of cloth 19, one edge portion of which is secured to the inner face of the envelope, inwardly 75 of the strip 17, and its other edge portion secured to the outer face of the lower, or inner envelope, while the intermediate portion of the strip 19 is secured to the other portion of the fold 18. The free end of the strip 17 has secured thereto one edge portion of a strip of cloth 20, whereby to form 80 a double thickness for the free end, which is grasped to pull the envelopes out into jalousied arrangement. The other edge portion 85 of the strip 20 is secured to the outer or upper face of the closed end of the outermost of the envelopes 16.

On the open ends of the envelopes are 90 adapted to be written the names, or other information with regard to the two faces of the record, and when the envelopes are pulled out into jalousied position, all of 95 these bits of information are simultaneously exposed to view, thus enabling the person to quickly locate the desired record, without the necessity of turning over each of the envelopes, and pulling out the records to find the record wanted.

When the book is closed, the envelopes 100 will assume the normal position, shown in Figure 2, after the manner of the ordinary record books of this type.

What is claimed is:

1. A book for disk records including a 110 pair of hinged boards, a plurality of record-receiving envelopes between the boards, a flexible connecting means between the closed

2 ends of the envelopes comprising a strip of material having one end secured to one of the boards and the other end free, said strip having a plurality of folds one portion of each of which is secured to one face of the closed end of an envelope, and means between the closed ends of the envelopes and secured thereto and to the other portions of the folds of the connecting means for 10 spacing the closed ends of the envelopes.

5 2. A book for disk records including a pair of hinged boards, a plurality of record-receiving envelopes between the boards, and

flexible connecting means between the closed ends of the envelopes comprising a strip 15 of material having a plurality of folds one portion of each of which is secured to one face of an envelope with the other portion free, and strips secured to the mutually adjacent faces of adjacent pairs 20 of envelopes and with their intermediate portions secured to the other portions of the folds of the first strip.

In testimony whereof, I affix my signature.

ELLSWORTH GABEL.
